UNITED STATES PATENT OFFICE

CHARLES C. MUELLER, JR., AND DANIEL C. WENDEL, OF NEWARK, NEW JERSEY, AS
SIGNORS TO WENDEL CO. INC., OF NEWARK, NEW JERSEY

SIGN

Application filed June 27, 1929. Serial No. 374,033.

This invention relates to signs, and more particularly to means for suspending a signboard or plate in a vertical position. The type of sign is commonly known as the side-walk sign.

One object of the invention is to provide a support upon which a signboard is pivotally mounted intermediate its height on a horizontal axis.

Another object of the invention is to provide a frame for the sign which is open at one end and which makes the sign easily accessible for replacement of signs, a locking means being provided for holding the signs in place.

Another object is to provide a counter weight at the lower end of the frame to normally hold same in a vertical position.

Another object is to construct the supporting member in such a way to enable same to be moved to a compact position for packing without dismantling and also to provide a means for locking same when in supporting position.

Still further objects of the invention will be set forth in the following description and drawings, in which:—

Fig. 1 is a perspective view of our device in set position;

Fig. 2 is a side elevational view with parts broken away showing upper and lower portion of the frame in section; also showing in dot and dash lines the position of the supporting legs for packing;

Fig. 3 is a sectional view taken on the lines 3—3 of Fig. 2; and

Fig. 4 is a sectional view taken on the lines 4—4 of Fig. 2, showing the side channel members.

The device consists of a frame 10 which encloses a sign member 12, and a stand 14 for supporting said frame 10.

The frame 10 comprises two vertical side members 16 of channel cross-section, a top horizontally disposed member 18, also of channel cross-section, which is welded to the top portion of the members 16 at 17, and two lower binding members 20 welded to the

lower portion of the members 16 at 19. The lower members 20 are shown in the drawings

as angle iron but any other suitable material may be used. This structure forms a frame which is closed on three ends and open at the bottom, as shown at 22, Fig. 2.

The stand comprises two substantially U-shaped members 24 which are assembled as shown in Fig. 1. Pivot pins or trunnions 26 project outward from each side of members 16 and are adapted to engage holes 28 in vertically disposed extensions 29 of legs 30, said legs being bent outward in an inverted V shape to provide sufficient support for the frame 10 and sign 12. The pins 26 may be secured to the members 16 by spot welding or in any other suitable manner. Spacing washers 32 are placed over the pins between the members 16 and the legs 30 to prevent the frame 10 from striking the stand 24 when said frame is caused to swing about its pivot if struck or blown by the wind.

Pins 34 riveted to the inside legs 30 of the stand 24 lock the stand in the position shown in Fig. 1 when the holes 36 in the outer legs 30 engage the pins 34. When the device is to be packed for shipping, the outer legs 30 are sprung slightly outward to release same from engagement with the pins 34 and then are raised to the position shown in dot and dash lines Fig. 2. This enables the device to be placed in a narrow compartment thereby saving shipping space.

The sign comprises two sign plates 38 which are placed in the frame through the open end 22 with a filler pad 40 of some resilient material, such as corrugated cardboard or the like, inserted between the two plates. A bolt 42 placed in holes 44 in the counterweight member 20 holds the sign plates and filler in place.

From the foregoing it will be observed that a very simple structure has been designed which can be easily constructed from inexpensive material and due to welding makes a very staple structure. This device can be used for either permanent signs or those which are changed frequently because of the simple means used to hold the signs in place.

Having described our invention, we claim:

1. A sign of the character described com-

prising a pivotally mounted frame, a stand for supporting said frame, an open lower portion in said frame adapted to receive sign plates and a filler placed between said plates, 5 a counterweight secured to the lower portion of said frame which forms a binder and provides the opening through which the sign plates and filler are inserted, and a stop member in said counterweight to prevent the signs from falling out.

10 2. A sign of the character described comprising a frame, a sign within said frame, a stand to support the frame, said stand comprising two substantially U shaped standards having angularly bent legs and vertically disposed extensions projecting upward therefrom, trunnions projecting from the sides of the frame adapted to be mounted in said vertically disposed extensions and 15 about which the leg portions are adapted to swing to a closed position, projecting pins fixed to one pair of extensions adapted to engage apertures in adjacent extensions to retain the legs in their open position.

20 3. A sign of the character described comprising a frame the top and sides of which are constructed from channel bars and the bottom of angle irons, an opening between said angle irons to receive a sign, a locking member in said angle irons to secure the sign, a collapsible stand comprising two substantially U shaped standards having angularly bent legs and vertically disposed extensions pivotally joined near the upper 25 ends thereof to the frame, projecting pins secured to one pair of the vertically extending portions of said standards, and apertures opposite said pins in the other vertically extending standard portions, adapted 30 to be engaged by said pins to lock the stand in open position.

35 In witness whereof we have hereunto set our hands.

CHARLES C. MUELLER, JR.
45 DANIEL C. WENDEL.
